UNITED STATES PATENT OFFICE.

WILLIAM JOHNSTON, OF PHILADELPHIA, PA., ASSIGNOR, BY DIRECT AND MESNE ASSIGNMENTS, OF TWO-THIRDS TO WILLIAM W. SHOE, OF SAME PLACE.

UNIVERSAL SHAFT-COUPING.

SPECIFICATION forming part of Letters Patent No. 243,914, dated July 5, 1881.

Application filed March 26, 1881. (No model.)

To all whom it may concern:

Be it known that I, WILLIAM JOHNSTON, a citizen of the United States, residing in the city and county of Philadelphia, State of Pennsylvania, have invented a new and useful Improvement in Universal Shaft-Couplings, which improvement is fully set forth in the following specification and accompanying drawings, in which—

10 Figure 1 is a side elevation of the coupling embodying my invention. Fig. 2 is a longitudinal section thereof in line xx , Fig. 1. Fig. 3 is a face view thereof. Fig. 4 is a section of a modification in line zz , Fig. 5. Fig. 5 is a transverse section thereof in line yy , Fig. 4. Fig. 6 is a longitudinal section of another modification. Fig. 7 is a perspective view of one of the gudgeons of the coupling.

Similar letters of reference indicate corresponding parts in the several figures.

20 My invention relates to improvements in shaft-coupling, wherein the shafts are allowed perfect freedom of motion in every direction within certain limits; and it consists in connecting the ball and socket of the coupling by means of rocking gudgeons, the construction and operation whereof will be hereinafter more fully set forth.

25 Referring to the drawings, A represents the shell of the coupling, having at one end an opening for the attachment of a shaft, and formed at the other end with a socket, B, for the reception of a ball, C, in the opening of which latter another shaft may be keyed or otherwise attached. The socket B is transversely pierced at opposite places for the reception of gudgeons D, the inner end of each of which is formed with a head, D', which is let into a countersink on the inner face of the 30 socket, and the ball C is circumferentially grooved, as at a , to receive the heads D' of the gudgeons, whereby, when the ball is moved, said heads ride freely in said groove a , restrained by the walls thereof, the groove being 35 continuous, so that either end of the opening for the shaft may be presented. The motion of the shafts is communicated first to the ball and then to the gudgeons and shell, or vice versa, and consequently to the other shaft, so 40 that both shafts rotate as one. One shaft may

be set at an angle, as shown by the dotted lines, Fig. 2, or both shafts may be set at an angle, as shown in Fig. 6, the angle or inclination of the shaft or shafts varying as desired. When power is imparted to one of the shafts 55 it is communicated to the other shaft regardless of the angle or inclination of either shaft; and it will be seen that when the shaft is set at an angle, as the ball rotates within the socket, the gudgeons receive rocking motions, 60 while the heads D' of the same, which project into the groove a , conform to the positions assumed by the said groove, occasioned by the rotation of the ball, the coupling thus operating with ease and without binding, the construction being such that the parts are strong 65 and durable, and may be cheaply produced.

The gudgeons above described have rocking or partly-rotary motions about their axes, which motions are independent of the motion of the 70 shell.

The groove of the ball is cut away, flattened or reduced at opposite places of its circumference, as at b , the opening which receives the shaft appearing at said places b , it being noticed 75 that the faces of the heads D' are curved to conform to the curvature of the base of the groove a of the ball, and, consequently, when the ball is in operative position the heads or gudgeons prevent the displacement of the ball, 80 the rotary motions thereof, as has been stated, not being interfered with.

When the coupling is to be disconnected or separated the shaft which is connected to the ball is removed and the ball rotated until the 85 flat faces b are parallel with the heads of the gudgeons. The ball may then be lifted from the socket, or by overturning the latter the ball will drop out. The application of the ball to the socket is accomplished by bringing the 90 flat faces b in line or parallel with the heads of the gudgeons, and then slipping the ball into the socket; or, if the shell is upright, the ball will readily drop into the socket. The ball is then rotated until the flat faces clear 95 the heads of the gudgeons, and the opening for the shaft again appears, the curved faces of the gudgeons then being contiguous to the curved base of the groove a , and thus retaining the ball in position, the gudgeons being adapted, 100

when power is applied to either shaft, to rock as before stated.

If desired, a socket may be formed at each end of the shell and provided with a ball and 5 rocking gudgeons, as will be seen in Fig. 6; or the inner face of the socket may be grooved and the gudgeons pivoted to the ball, as shown in Figs. 4 and 5, in which case the socket is made in detachable sections, so that the ball 10 may be applied, held in position, and removed when desired.

Furthermore, if desired, the rocking gudgeons may be of the form of spheres or pins, 15 loosely let into one part of the coupling and projecting freely into the other.

The head D' of each gudgeon is beveled at D² on its outer end or edge, to allow the shafts, or either of them, to have the fullest possible 20 inclination. The same general object may be effected by beveling the edge of the socket, but this construction requires the heads to be made too small, or else the unbeveled outer 25 ends of the head would get in the way. If the gudgeons are set farther back in the socket to avoid this difficulty, the socket must be made larger, and therefore clumsier, than in the

construction which I employ. The line of inclination of bevels D² passes sufficiently behind the center of the ball to allow the shaft attached to said ball to be turned against the 30 face.

Having thus described my invention, what I claim as new, and desire to secure by Letters Patent, is—

1. Socket B, in combination with gudgeons 35 D D and ball C, which is provided with an annular groove to receive the heads of the gudgeons, said groove being flattened at opposite sides where the shaft passes through, substantially as described.

2. The shell B, ball C, and the two shafts, in combination with gudgeons D, the heads D' of which are beveled at their outer ends on a line passing behind the center of the ball, for the purpose of allowing the shafts to have a 45 greater inclination than would otherwise be possible.

WILLIAM JOHNSTON.
